UNITED STATES PATENT OFFICE.

HERBERT W. HOOVER, OF BAYONNE, NEW JERSEY.

STEAM-BOILER GAGE-COCK.

1,072,850.

Specification of Letters Patent.

Patented Sept. 9, 1913.

Application filed December 31, 1912. Serial No. 739,448.

To all whom it may concern:

Be it known that I, HERBERT W. HOOVER, a citizen of the United States, residing at Bayonne, in the county of Hudson and State 5 of New Jersey, have invented new and useful Improvements in Steam - Boiler Gage-Cocks, of which the following is a specification.

This invention relates to valves, and particularly to gage cocks and has for its object to provide an improved mounting therefor, whereby all essential elements of the valve may be removed and replaced by a new device embracing the complete valve without 15 the necessity for relieving the pressure in the boiler, while it is operating under working pressure.

It is a purpose to permit the quick renewal of a cock in this way without the necessity for auxiliary valve elements operative when the main valve is to be renewed, which auxiliary might itself require removal at times.

It is also an aim to make it possible to 25 manufacture this invention at a low cost and enable its application with facility and without the requirement of special tools, or expert training.

Additional objects and advantages will be 30 apparent, some appearing from the following description and from the drawings, in which,

Figure 1 is a cross sectional view of the device applied to a boiler, Fig. 2 is a side 35 view at right angles to Fig. 1, Fig. 3 is a top view of the device, Fig. 4 is a plan of the base.

There is illustrated a section of a boiler 10, in which there is provided the usual threaded opening 11 for the reception of a cock. It is desirable that this opening be somewhat larger than that customarily made, however. Engaged in this opening 40 there is the threaded plug 12 of the base member 13 of my device, and formed therethrough, opening on the outer face of the body of the base there is the small inlet passage 14 communicating with the interior of the boiler. The outer body of the base 45 is rectangular in form, and is provided with a broad channel 15 thereacross, having the grooved sides 16 forming flanges 17 by which the cock body proper is retained as will be explained. Of a less diameter than 50 the width of the channel 15 there is a cir-

cular recess 18 formed concentrically around the passage 14, having beveled sides 19, and fitted therein there is an annulus 20 of a metal expansible under the action of heat such as that of steam; the outer face of 60 which annulus is accurately finished to a plane surface parallel with the inner surfaces of the flanges 17.

The cock proper comprises the casing 21 in which there may be fitted any form of 65 valve, the casing having an opening of smaller diameter than the annulus 20 and adapted to open therewithin when in operative position. This opening 22 in the casing as at present shown is of conical form 70 and concentrically therefrom there extends the bore 23 in which is fitted revolubly the stem 24 of the hollow conical valve head 25 fitting snugly in the conical opening, which may be termed a seat. Opening at one point 75 on this seat intermediately of its height there is an outlet passage 26, leading to and through the nozzle 27 on the side of the casing at a suitable point. The outer end of the casing is provided with stops 28 spaced 80 at suitable distance to check the handle 29 of the valve which is secured in a suitable manner to the outer end of the stem 24.

The casing is provided with a rectangular base 30 of suitable thickness, being of a 85 width to snugly fit in the channel 15 and against its sides. The edge portions at two sides are also finished to fit snugly but readily slidably against the flanges 17, when the annulus 20 engages the intermediate surface 90 of the bottom face of the base around the conical seat. Suitable openings 31 are formed around the base 30 registered with threaded openings 32 in the base 13, through which suitable bolts 33 may be engaged to 95 hold the device in place. Across the outer or top face of the base 30 adjacent the right hand end there is formed a groove 34 having a depth a little more than half the thickness of the base, and the outer edge portion 100 outwardly of this groove is cut away parallel with the top face of the base 30 and spaced therebelow a little less than half the thickness of this base, forming what may be termed a rib 35. The opposite or left 105 hand end is formed similarly except that the groove and rib 36 and 37 respectively are presented toward the bottom of the device. By this construction the right hand side of a similarly formed cock may interlock with 110

the left hand side of the cock described and as the latter is slipped out of the channel 15 the other may follow it, maintaining closed connections between the two mean- 5 while, and abutting the ring 20 snugly enough to prevent the escape of an objectionable amount of steam.

In practice I have found that the ring 20 made of what is commercially known as 10 "Muntz metal" operates satisfactorily, and to facilitate the slipping of the new valve into place its bottom should be oiled, as well as the sides and top where the flanges engage.

15 What is claimed:

1. A device of the class described comprising a base member adapted to be engaged in a boiler or the like and having a channel there-across having inwardly projecting flanges at 20 the sides, a circular recess centrally of the channel and spaced from the ends of the base, a seat surface around the recess finished to an accurate plane surface, a steam passage opening from the recess through the base for 25 communication with the interior of a boiler, and a cock member including a base portion adapted to fit snugly in the channel and under the flanges, the ends of the base portion

being shaped for interlocking engagement with the ends of a similarly formed member. 30

2. A device of the class described comprising a base member adapted to be engaged in a boiler, having a transversely channeled portion adapted to set without the boiler, the channeled portion having overhanging 35 sides, in combination with a cock base having sides adapted for snug engagement slid- ably in the channeled base, the channeled base and cock base having opposed seat portions adapted to make a steam-tight joint, the end 40 edges of the cock base having transversely formed grooves and projections adapted for interlocking engagement with the ends of a similar member for sliding movement of the two members in the channeled base in inter- 45 locked relation, a steam passage being formed through the cock base, and valve means for closing and opening the passage.

In testimony whereof I have hereunto set my hand in presence of two subscribing 50 witnesses.

HERBERT W. HOOVER.
